STITCHLESS WALLET CONSTRUCTION

Francis A. Brady, Canandaigua, N. Y., assignor
to Hickok Manufacturing Company, Inc., Rochester, N. Y., a corporation of New York

Application July 29, 1949, Serial No. 107,599

1 Claim. (Cl. 150—38)

1

The invention relates to a stitchless wallet construction.

An object of the present invention is to provide a simple, practical and highly attractive stitchless wallet of strong, durable and inexpensive construction, having a compartment for bills and provided with a dividing strip or partition retained in position and concealed at its upper portion by top marginal flaps of the outer wall of the wallet to form a concealed compartment especially adapted for holding bills of high denominations, checks, and other papers so that when the wallet is opened, only a second bill holding compartment, designed for holding bills of small denomination, is disclosed to view.

A further object of the invention is to provide a stitchless wallet comprising an outer wall having pocket forming members, and a separate inner wall positively interlocked with the pocket forming members by means carried by flaps of said members and engaging slots in the terminal portions of the inner wall.

Another object of the invention is to provide a window in one of the pocket forming members having a frame with which an end flap of the outer wall is interlocked to assist in retaining said end flap securely fastened in position in overlapping relation with the outer side portion of the pocket forming member and at the same time reinforce the latter.

A further object of the invention is to provide a reinforcement for the other pocket forming member and the flap thereof and to equip such pocket forming member with an insert cooperating with such pocket forming member to form a plurality of pocket compartments and removable and reversible to vary the number of such pocket compartments.

Another object of the invention is to provide a stitchless wallet having an outer wall provided at the top with downwardly or inwardly extending dividing strip retaining and concealing flaps and with terminal tabs secured to the outer wall at the inner face thereof, said marginal flaps and tabs being formed by an integral extension of the top portion of the outer wall.

With the above and other objects in view, the invention consists in the construction and novel combination and arrangement of parts herein-after fully described, illustrated in the accompanying drawings and pointed out in the claim hereto appended, it being understood that various changes in the form, proportions, and minor details of construction, within the scope of the claim, may be resorted to without departing from

2

the spirit or sacrificing any of the advantages of the invention.

In the drawings:

Fig. 1 is an elevation of the stitchless wallet constructed in accordance with this invention and shown in open position;

Fig. 2 is a longitudinal sectional view on the line 2—2 of Fig. 1;

Fig. 3 is a longitudinal sectional view on the line 3—3 of Fig. 2, showing portions of the dividing strip and the top marginal flanges and tabs of the outer wall in elevation;

Fig. 4 is a transverse sectional view on the line 4—4 of Fig. 1;

Fig. 5 is a transverse sectional view on the line 5—5 of Fig. 1;

Fig. 6 is a plan view of the blank from which the outer wall, the pocket forming members and the flaps and tabs are formed;

Fig. 7 is a plan view of the inner wall;

Fig. 8 is a detail perspective view of the pocket insert, partly open to show the two sides or leaves thereof;

Fig. 9 is a detail view of the reinforcement of the pocket forming member having the insert;

Fig. 10 is a similar view of the reinforcement of the flap of such pocket forming member;

Fig. 11 is an elevation of a modification of the invention in which the dividing strip or partition is secured to the outer wall by a zipper fastening;

Fig. 12 is a detail vertical sectional view taken on the line 12—12 of Fig. 11.

Referring particularly to the form of the invention illustrated in Figs. 1 to 10, inclusive, of the drawings, 1 designates an oblong outer wallet wall constructed of leather or other suitable flexible sheet material and provided at the bottom with pocket forming members 2 and 3 extending upwardly in parallelism with the outer wall and provided at the top with flaps 4 and 5 which fold downwardly and inwardly within the wallet over an oblong inner wall 6.

The flaps are preferably tapered slightly by arranging their lower edges 7 and 8 divergently at an inclination, and the outer ends of the flaps 4 and 5 are provided with parallel slits 9 and 10 forming tongues 11 located at a point spaced from the upper and lower edges of the flaps 4 and 5 and extending longitudinally of the wallet through vertical transverse slots 12 formed in the end portions of the inner wall 6, whereby the inner wall which is confined in cooperative relation with the pocket forming members by the flaps is positively interlocked with said flaps.

The pocket forming members 2 and 3 cooperate

with the inner wall to provide main exterior pockets at the inner face or inside the wallet which is foldable transversely in the conventional manner.

The flaps 4 and 5 are of greater length than the pocket forming members and their outer ends extend beyond the ends of said members to interlock with end flaps 13 and 14 of the outer wall, as hereinafter fully explained.

The pocket forming member 2 is provided with a window formed by a sheet 15 of Celluloid or other transparent material, and a rectangular opening 16 cut in the member 2 and providing a frame for the transparent window sheet which is adhesively secured to the frame portion of the member 2. Any suitable adhesive or other means may be employed for securing the transparent window sheet to the pocket forming member 2 at the opening 16 thereof.

The other pocket forming member 3 is provided with a transverse slit 17 which extends upwardly at a slight inclination when the pocket forming member is in pocket forming position, and the said member 3 is provided at its inner face with a reinforcement 18 consisting of a sheet of flexible material conforming to the configuration of the member 3 and provided with a slit 19 which coincides or registers with the slit 17 of the member 3 to permit a compartment forming insert 20 to be inserted in and partially passed through the slit 17 of the member 3. The reinforcement 18 is adhesively secured to the inner face of the member 3.

The flaps 4 and 5 of the members 2 and 3 are each provided with a reinforcement 21 consisting of a sheet of flexible material conforming to the configuration of the flap and adhesively secured to the inner face of the same and provided with spaced parallel slits 22 forming tongue portions 23 which reinforce the tongues 11 of the flaps.

The end flaps 13 and 14 of the outer wall 1, which are foldable around the pocket forming members and are adhesively secured to the same for closing the outer ends of the pockets, are provided with dovetail extensions 24 and 25 forming interlocking tongues which extend longitudinally of the end flaps and which have converging end edges 26 and 27. The tongue 24 of the end flap 13 is extended between the transparent sheet 15 and the frame portion 28 of the member 2, the said frame portion 28 being left free for this purpose, and as the outer portion of the inwardly tapered tongue is of slightly greater length than the width of the opening 16, the end edges 26 extend beyond the opening 16 and thereby interlock the tongue with the member 2. The end flap 13 and the adjacent side portion of the flap 4 of the member 2 are adhesively secured to the member 2 when the end flap is folded over the same and the tongue or extension 24 is interlocked therewith.

The tongue 25 and the end flap 14 at the other end of the outer wall are folded inwardly over the member 3 and said tongue 25 is extended through a vertical slit 25a of the pocket forming member and is interlocked with the same when the end flap 14 is folded over the pocket forming member and the tongue inserted in said slit 25a. It will thus be seen that both end flaps of the outer wall are adhesively secured to the members 2 and 3 and are also interlocked with the same by means of the tongues or extensions 24 and 25 of the end flaps. After the tongues or extensions 24 and 25 are passed through the pocket forming members they are folded outwardly with respect

to the inner edges of the marginal flanges 13 and 14 and when in interlocked relation with the pocket forming members they lie beneath the marginal end flaps 13 and 14 and are located wholly within the contour of the same. The marginal end flaps provide a narrow edging for the outer ends of the exteriorly arranged pockets formed by the said members and the outer side of the window opening of the pocket forming member 2 is framed by the adjacent narrow marginal end flap 13.

The inner wall 6 is provided at the central portions of its upper and lower edges with narrow extensions 29 and 30 which are folded against the inner face of the inner wall and adhesively secured to the same to reinforce the central portion of the inner wall. The outer wall is provided at the bottom between the members 2 and 3 with a central tab 31 which is folded against the inner face of the outer wall and adhesively secured to the same to reinforce the lower edge of the inner wall between the pocket forming members.

Within the wallet between the inner and outer walls is arranged a dividing strip 32 consisting of an oblong sheet of flexible material and having its upper marginal portion 33 bent or folded downwardly and adhesively secured to the rear face of the dividing strip to reinforce the same. The upper corners of the dividing strip are cut away at 34 and the central portion 35 of the lower edge is recessed or cut away to span the bottom central tab 31 of the outer wall. The lower corners 36 of the dividing strip are also cut away and the lower edge 31 of the dividing strip is adhesively secured to the inner and outer walls at the lower edges thereof. The dividing strip and the outer wall form a secret bill compartment and the upper edge of the dividing strip is engaged and concealed by upper flaps 38 formed by an upper marginal extension 39 of the outer wall. The upper marginal extension 39, which is folded downwardly and inwardly within the wallet, is slit at 40 adjacent its ends and is also cut away at 41 at its central portion to form the upper flaps 38 and also to provide end tabs 42 which are bent downwardly into the wallet and adhesively secured to the inner face of the outer wall. The slits 40 terminate short of the upper edge of the outer wall and maintain the inwardly folded marginal portion of the outer wall within the wallet.

The upper reinforced edge of the dividing strip is spaced from the upper edge of the outer wall and is located between the outer wall and the top flaps 38 which confine the dividing strip contiguous to the outer wall to form the secret bill compartment and also partially conceal the dividing strip. The dividing strip and the front wall form a bill receiving compartment which is exposed when the wallet is opened and the front and rear walls spread to afford access to such compartment. The exposed compartment is designed to contain bills of small denominations and the secret compartment is provided for the reception of bills of higher denominations and checks and other papers desired not to be exposed when the wallet is opened for the removal of one or more of the bills of small denomination. The cut away upper corners at 34 expose the upper corners of the bills contained within the concealed compartment and facilitate ready removal of the contents of the concealed compartment when the same is opened.

The removable and reversible insert consists

of a substantially oblong piece of sheet material which is folded transversely to form two outer leaves 43. The member 3 and the inner wall form a main pocket and the insert 20, which is of a length to project exteriorly beyond the slit 17, is adapted to form with the said member 3 an inner additional pocket and an outer additional pocket when the fold of the member 20 is in a projecting position. The inner additional pocket is located between the insert and the inner wall of the wallet and the outer additional pocket is located between the insert and the pocket forming member. These pockets are in addition to the pocket or pockets between the two outer leaves 43 of the insert. When the insert is reversed and the fold of the insert is arranged interiorly of the member 3, the leaves 43 provide a central additional pocket in addition to the inner and outer additional pockets. Also the insert may be removed and the leaves will provide a concealed pocket if the insert is returned with the fold projecting exteriorly of the member 3.

In the modification illustrated in Figs. 11 and 12, the wallet construction is substantially the same as that heretofore described with the exception that the top flaps of the outer wall for concealing and confining the upper edge of the dividing strip are omitted and the upper edge of the dividing strip is secured to the upper portion of the outer wall by a zipper fastener composed of a longitudinal row of slide fastener elements 44 secured to the inner face of the outer wall adjacent the upper edge thereof and a longitudinal row of slide fastener elements 45 secured to the dividing strip at the upper edge thereof, and a slide member 46 which engages the slide fastener elements in the usual manner to form a zipper fastener.

The upper marginal portion 47 of the material forming the outer wall 48 is folded inwardly to reinforce the outer wall at the upper edge thereof and the flexible strip 49 of material carrying the slide fastener elements 44 is attached to the inner face of the outer wall between the same and the said marginal portion 47. The flexible strip 50 which carries the slide fastener elements 45 is secured to the dividing strip at the upper edge thereof. The dividing strip, as in the form of the invention illustrated in Figs. 1 to 10, inclusive, divides the interior of the wallet into two bill compartments and the bill compartment between the dividing strip and the outer wall is closed and fastened by the zipper fastener.

The terminals of the flexible strips which are provided with the slide fastener elements 44 and 45 are secured to the outer wall and to the top end tabs 51 thereof.

5 I claim:

A stitchless wallet comprising inner and outer walls, the inner wall consisting of a single piece of material and extending longitudinally of the wallet from one end of the outer wall to the other 10 end thereof and the outer wall being provided with pocket forming members connected with the lower edge of the outer wall and extending upwardly therefrom to the upper edge of the inner wall and fitted against the outer face of 15 the same and having flaps extending downwardly at the inner face of the inner wall to approximately the lower edge thereof and confining the inner wall within the wallet and securing said pocket forming members to said inner wall, and 20 narrow marginal end flaps formed integral with and located at the ends of the outer wall and folded inwardly over the outer side edges of the pocket forming members and providing narrow edgings and having narrow extensions forming 25 tongues of a width and length less than the marginal end flaps and extending through the pocket forming members to the inner faces thereof and having terminal projections engaging the inner faces of the pocket forming members and positively interlocking the tongues with 30 said pocket forming members to prevent withdrawal of the tongues from the inner faces of the pocket forming members.

FRANCIS A. BRADY.
